CLAIM

The ornamental design for martial arts practice stand, as shown and described.

DESCRIPTION

FIG. 1 is a top perspective view from above of the martial arts practice stand of my design;

FIG. 2 is a front elevational view of my design of FIG. 1, with the back elevational view being the same;

FIG. 3 is a side elevational view of my design of FIG. 1, with the other side being the same; and,

FIG. 4 is a top plan view of my design of FIG. 1, with the bottom being unornamented.

FIG. 1

FIG. 2

FIG. 4
